UNITED STATES PATENT OFFICE.

BERNARD J. MADDEN, OF DULUTH, MINNESOTA.

BOX FOR POURING STEEL INGOTS.

Application filed January 14, 1927. Serial No. 161,166.

The present invention appertains to boxes for pouring steel into molds, and has for one of its objects to provide a structure of this character whereby more molds can be filled 5 at one operation, the flow of steel through the molds being controllable at all times so that more or less of the molten steel can be directed to either of the molds.

Another very important object of the invention resides in the provision of a pouring box whereby the ingots will be poured slowly thus doing away with the cracking resulting from rapid pouring of the steel. It is well known to those skilled in the art that unless 15 the ingots are poured slowly, the cracks will be produced and this has resulted to a use to a large extent of a plate known as a bottom shaft. Such ingots are more expensive to manufacture than top cast ingots. The 20 present invention, however, produces top cast ingots with all the advantages of the bottom cast ingots but at a much lower cost.

A still further very important object of the invention is to provide a pouring box whereby by reducing the flow of steel the formation of cracks is practically eliminated, the pressure of the stream as it comes from the ladle being taken up by the pouring box and said stream being split so that a portion 30 will go to one pair of molds and the balance to the other pair of molds, the flow being much slower than should the steel be poured directly from the ladles into the molds.

With the above and numerous other objects in view as will appear as the description proceeds, the invention resides in certain novel features of construction, and in the combination and arrangement of parts as will be hereinafter more fully described and 40 claimed.

In the drawings:

Figure 1 is a side elevation of an assembly embodying the features of my invention,

Fig. 2 is a horizontal longitudinal section 45 through the pouring box,

Fig. 3 is a vertical longitudinal section therethrough,

Fig. 4 is an end view of the assembly shown in Figure 1.

Referring to the drawing in detail, it will be seen that the numerals 5 denote the rails of track on which the wheels 6 of trucks 7 rise. Molds 8 are mounted on the tracks 7, there preferably being two molds on each 55 truck and two trucks coupled together. The numerals 9 and 10 denote tiers. A rail 11

is disposed on tiers 9. A table 12 is partially mounted on tiers 10 and supports a rail 13 forming with rail 11 a trackway for wheels 14 journaled on axles 15. My improved pouring box B is mounted on the axles 15.

The box B includes a bottom 17 having openings 18 one to each side of the center thereof and openings 19 one adjacent each end thereof. Walls 20 rise from the side edges of the bottom 17. End walls 21 rise from the end edges of the bottom 17 and are curved inwardly as at 22 to provide horizontal extensions 23. The centers of the side walls 20 are extended upwardly to form with walls 24 a hopper 25 into which the molten steel is poured from ladles. Detachable housings 26 are engaged between the inner ends of extensions 23 and the walls 24. Brick linings 27 is provided for the interior of the pouring box. Gates 28 are mounted on rods 29 slidably through openings in the upper portions of the housings 26 and are controlled by levers 30 pivotally mounted as at 31. Thus the gate 28 may be raised and lowered so that when desired the ends of the boxing may be cut off so that no molten steel will flow through the openings 19 or these gates 28 may be lowered to retard the flowing 35 of the steel through the openings 19 as may be desirable. Stoppers 32 are movable in and out of opening 18 and are mounted on rods 33 slidable through openings in the walls 24 and pivotally engaged with levers 34 which are pivoted as at 35. Hatches 36 are mounted on the levers 34 and are engageable with stops 37 to hold the stoppers 32 in open position when desired.

A brick 39 rests on the brick lining 27 on 40 the bottom 17 and has a baffle roof 40 disposed thereover. This roof includes sides 41 which slant upwardly and inwardly towards each other and ends 42 which slant upwardly and inwardly towards each other, said sides 100 and ends 41 and 42 respectively being provided at their bottoms with openings 43. The brick 39 functions as a hearth and has aluminum 45 thereon so that the molten steel poured into the hopper will be fused and quickened.

From the above detailed description it will be seen that I have devised a new and useful casting machine for pouring steel ingots. This machine or box enables the molten steel 110 to be poured into more molds at one time. In the molten state, steel is capable of dis-

solving large volumes of gases such as oxygen, carbon monoxide, nitrogen and hydrogen. These gases form blow-holes which become filled with liquid oxide of iron and do not weld in the making of seamless pipe and the like. These are known in the art as cracks and it is necessary to chip them at a large expense. My apparatus, however, slows down the pouring of the steel and gives the same time to quicken. The stream is split by the baffle roof 42 and the two streams thus formed may be regulated by a proper operation of the stoppers 32 and the gates 28.

It is thought that the construction, operation, utility, and advantages of this invention will now be clearly understood by those skilled in this art without a more detailed description thereof. The present embodiment of the invention has been disclosed in detail merely by way of example since in actual practice it attains the features of advantage enumerated as desirable in the statement of the invention and the above description and has proved exceedingly handy and easy to manipulate. It is apparent, however, that changes in the details of construction and in the combination and arrangement of parts may be resorted to without departing from the spirit or scope of the invention as hereinafter claimed or sacrificing any of its advantages.

Having thus described my invention, what I claim as new is:—

1. A box for pouring steel ingots comprising a bottom having a plurality of openings, means for controlling the flow of molten steel through said openings, said box including an entrance hopper, and a baffle on the bottom below the hopper to split the

stream of molten steel, said baffle being in the form of a roof having openings in the bottom edges thereof, and a brick on the bottom under the roof for supporting a quantity of aluminum.

2. A box for pouring steel ingots comprising a bottom having a plurality of openings one to each side of the center and one at each end, gates movable across the box between the end and intermediate openings, means operable from the exterior of the box for moving the gates.

3. A box for pouring steel ingots comprising a bottom having a plurality of openings one to each side of the center and one at each end, gates movable across the box between the end and intermediate openings, means operable from the exterior of the box for moving the gates, stoppers associated with the intermediate openings, and means operable exteriorly of the box for controlling said stoppers.

4. A box for pouring steel ingots comprising a bottom having a plurality of openings one to each side of the center and one at each end, gates movable across the box between the end and intermediate openings, means operable from the exterior of the box for moving the gates, stoppers associated with the intermediate openings, and means operable exteriorly of the box for controlling said stoppers, a hearth brick on the bottom between the intermediate openings for supporting a quantity of aluminum, and a baffle roof over said hearth brick and having its bottom edges provided with openings.

In testimony whereof I affix my signature.

BERNARD J. MADDEN.
